UNITED STATES PATENT OFFICE.

ROLAND B. MANNING AND LEE R. MOORE, OF DALLAS, TEXAS.

STEAM-GENERATOR.

1,350,554.

Specification of Letters Patent. Patented Aug. 24, 1920.

Application filed March 17, 1919. Serial No. 283,177.

To all whom it may concern:

Be it known that we, ROLAND B. MANNING and LEE R. MOORE, citizens of the United States, residing at Dallas, in the 5 county of Dallas and State of Texas, have invented certain new and useful Improvements in Steam-Generators, of which the following is a specification.

This invention relates to new and useful 10 improvements in steam generators.

The object of the invention is to generate a volume of steam in an economical and efficient manner with a minimum fuel consumption.

15 In carrying out the invention a plurality of generating fingers or tubes are disposed in the path of the heat arising from a suitable fire. Water is introduced in the lowermost fingers and is generated into steam

20 which travels upward through connections between the tubes and is carried off for use.

Other details will be more specifically pointed out together with novel features and modifications.

25 The invention will be more readily understood from a reading of the following specification and by reference to the accompanying drawings, in which an example of the invention is shown and wherein:

30 Figure 1 is a vertical sectional view,

Fig. 2 is a vertical sectional view at right angles to Fig. 1,

Fig. 3 is a rear elevation of the generator,

Fig. 4 is a cross-sectional detail on the line 35 4—4 of Fig. 3,

Fig. 5 is a cross-sectional detail on the line 5—5 of Fig. 3,

Fig. 6 is a cross-sectional detail on the line 6—6 of Fig. 2,

40 Fig. 7 is a vertical sectional view of a modified form,

Fig. 8 is a vertical sectional view of the same at right angles thereto, and

Fig. 9 is a cross-sectional view on the line 45 9—9 of Fig. 7.

In the drawings the numeral 1 designates an inclosing structure which may be built of fire brick or other suitable material and may assume different shapes. At the bottom 50 of the structure a fire grate 2 is disposed and gas burners 3 may be used thereon in lieu of other fuel. A vertical metal distributing drum 4 is embedded in the rear of the structure.

55 From the face of the drum generating fingers or tubes 5 extend forward and termi-

nate near the front wall. The front ends of the fingers are closed and said fingers are disposed in series or courses, each at a different elevation and each course including a 60 plurality of fingers. On the outer side of the rear wall of the drum transverse hollow bosses or conduit 6 and 7 respectively, are cast in superposed order. The bosses are opposite the rear ends of the fingers. A 65 horizontal partition 8 is arranged between boss 6 and the lowermost boss 7. This partition forms a separate chamber in the lower portion of the drum.

A water manifold 9 has branches 10 entering the front ends of the lowermost fingers and provided with spray-caps or heads 11. The water under pressure is thus sprayed into the front ends of the lowest course of fingers. The steam and water 70 from the lowest course of fingers is discharged into the drum below the partition. The said steam and water enter the boss 6 through a slot 12 (Figs. 2 and 5) and pass to a riser 13 cast on the rear face of the 75 drum and communicating with each of the bosses 7 through a valve seat 14. A valve 15 is provided for each seat and is controlled by a hand wheel and stem 16 so that the supply to any particular boss may be cut off if 80 desired.

Spray nozzles 17 screw into the rear wall of the drum so as to communicate with the bores of the bosses 7. These nozzles are considerably less in diameter than the internal 90 diameter of the fingers into which they project. Spray caps or heads 18 are mounted on the forward ends of the nozzles, a short distance from the closed ends of the fingers. The water and steam from the riser flows 95 into the bosses and through the nozzles to the caps 18. The spray ejected from the caps 18 contacting with the heated fingers forms a vapor which travels rearwardly in the fingers to the drum.

A steam outlet pipe 19 leads from the top of the drum to a storage tank 20 from which a supply pipe 21 extends. Baffle plates 22 extend transversely of the structure 1 between the courses of the fingers in staggered 105 relation so that the heat currents from the grate 2 must pursue a circuitous path and finally escape through an outlet 23 to a stack 24. For cleaning the caps 18 we provide a cross connecting pipe 25 communicating with all of the lower course of fingers and provided with a cut-off valve 26. By 110

opening this valve a reaction is had which tends to reverse the pressure in the fingers, thus drawing water back through the perforations of the caps 18 and removing deposits from the inside of the same.

5 In Figs. 7 to 9 we have shown a modified form in which the fingers 5 screw direct into horizontal pipe members 30 embedded in a back wall 31 and connected centrally by short 10 pipes 32 forming a riser extending through all of the members. A stock 33 leads from the top of the inclosing structure 1. A water feed pipe 34 enters the bottom member 30 and includes a cut-off valve 35. A steam 15 pipe 36 leads from the top member to a tank or receptacle 37. A return pipe 38 leads from the tank to the pipe 34 for conveying the condensation back to the generator. It is obvious that the pipe 36 may lead 20 to a point of use of the steam and the pipe 38 may return from said point so that a circulatory system is had and the same water used over again, provided no steam is exhausted.

25 What we claim, is:

1. In a steam generator, a heating casing, a substantially vertical drum disposed near the heating casing and provided in its lower portion with a cross partition forming a 30 separate chamber, preheating tubes arranged within the heating casing and leading into the separate chamber, heating means for the heating casing, spaced tubular fingers arranged in superposed relation within the 35 heating casing above the preheating tubes and leading into the drum, supply tubes extending longitudinally within the tubular fingers and provided with outlet means, separate means of communication between 40 the outer ends of the supply tubes and the separate chamber, and steam outlet means having communication with the upper portion of the drum.

2. In a steam generator, a heating casing, 45 a substantially vertical drum disposed near the heating casing and provided in its lower portion with a cross partition forming a separate chamber, preheating tubes arranged within the heating casing and leading into the separate chamber, heating means for the heating casing, means to supply water to the preheating tubes, means to withdraw water from the preheating tubes, spaced tubular fingers arranged in superposed relation 50 within the heating casing above the preheating tubes and leading into the drum, supply tubes extending longitudinally within the tubular fingers and provided with perforations, separate means of communication 55 between the outer ends of the supply tubes and the separate chamber, and steam outlet means having communication with the upper portion of the drum.

3. In a steam generator, a heating casing, 60 a substantially vertical drum connected with

the heating casing and provided in its lower portion with a cross partition forming a separate chamber, preheating tubes arranged within the heating chamber and leading into the separate chamber, water supply means 70 leading into the opposite ends of the preheating tubes, a conduit carried by the drum and communicating with the separate chamber, a plurality of spaced superposed conduits carried by the drum and being free 75 from communication with the interior thereof, a riser carried by the drum and serving to connect the first named conduit and the spaced superposed conduits, supply tubes extending within the heating casing and 80 passing through the drum and having their outer ends leading into the spaced superposed conduits, said supply tubes having outlet means, tubular fingers arranged within the heating casing and receiving the supply tubes and leading into the drum, and steam outlet means having communication 85 with the upper portion of the drum.

4. In a steam generator, a heating casing, a substantially vertical drum connected with 90 the heating casing and provided in its lower portion with a cross partition forming a separate chamber, preheating tubes arranged within the heating chamber and leading into the separate chamber, means to supply water 95 to the preheating tubes, a transverse conduit carried by the drum and having communication with the separate chamber, a riser carried by the drum and having communication with the transverse conduit, a plurality of 100 spaced superposed conduits carried by the drum and being free from communication with the interior thereof and connected at their ends with the riser, a valve to control the passage of water from the riser to each 105 of the spaced superposed conduits, spaced superposed tubular fingers arranged within the heating casing and leading into the drum, supply tubes arranged within the tubular fingers and extending across the drum 110 and leading into the spaced superposed conduits, steam outlet means for the drum, and means for heating the heating casing.

5. In a steam generator, a plurality of horizontal generating fingers closed at their 115 outer ends, a substantially vertical drum from which the fingers extend, nozzles extending into the fingers, spray caps on the ends of the nozzles near the closed ends of the fingers, and a lower set of pre-heating 120 tubes extending from the lower portion of the drum and having their outer ends closed, feed water means entering the closed ends of the tubes, spray caps on the ends of the means within the tubes, a partition across 125 the lower portion of the drum above the tubes, a riser communicating with the drum below the partition, and distributing members on the drum leading from the riser and connected with the nozzles.

6. In a steam generator, a plurality of horizontal generating fingers closed at their outer ends, a substantially vertical drum from which the fingers extend, nozzles extending into the fingers, spray caps on the ends of the nozzles near the closed ends of the fingers, and a lower set of pre-heating tubes extending from the lower portion of the drum and having their outer ends closed, feed water means entering the closed ends of the tubes, spray caps on the ends of the means within the tubes, a partition across the lower portion of the drum above the tubes, a riser communicating with the drum below the partition, distributing members on the drum leading from the riser and connected with the nozzles, and valves controlling the passage of fluids from the riser to individual distributing members.
7. In a steam generator, an inclosing structure, a vertical drum arranged in one wall of the structure, spaced superposed tubular fingers extending from the drum horizontally into the structure, a cross partition in the lower portion of the drum, tubes 25 extending horizontally from drum beneath the cross partition, means for supplying water to the tubes, a hollow boss on the drum communicating with the latter below the partition, a riser on the drum extending 30 from the said boss, a plurality of spaced superposed hollow bosses on the drum above the partition and leading into the riser, and spray nozzles extending from the last named bosses into the fingers. 35
- In testimony whereof we affix our signatures.
- ROLAND B. MANNING.
LEE R. MOORE.
